R. WALDO

RUG

Filed April 23, 1924

Inventor
Raymond Waldo
By: Nixon & Crane
Attnys.

UNITED STATES PATENT OFFICE.

RAYMOND WALDO, OF ST. PAUL, MINNESOTA, ASSIGNOR TO CREX CARPET COMPANY,
OF NEW YORK, N. Y., A CORPORATION OF DELAWARE.

DESIGN FOR A RUG.

Application filed April 28, 1924. Serial No. 9,419. Term of patent 3½ years.

To all whom it may concern:

Be it known that I, RAYMOND WALDO, a citizen of the United States, residing at St. Paul, in the county of Ramsey and State of Minnesota, have invented a new, original, and ornamental Design for a Rug, of which the following is a specification, reference being had to the accompanying drawing, forming a part thereof.

The figure is a plan view of a rug showing my design.

I claim:

The ornamental design for a rug, as shown.

St. Paul, Minnesota, April 23rd, 1924.

RAYMOND WALDO.
